UNITED STATES PATENT OFFICE.

ALLEN W. CROUSHORE, OF LINCOLN PLACE, PENNSYLVANIA.

ATTACHMENT FOR TYPE-WRITERS.

No. 878,941.

Specification of Letters Patent.

Patented Feb. 11, 1908.

Application filed July 12, 1907. Serial No. 383,451.

To all whom it may concern:

Be it known that I, ALLEN W. CROUSHORE, a citizen of the United States of America, residing at Lincoln Place, in the county of 5 Allegheny and State of Pennsylvania, have invented certain new and useful Improvements in Attachments for Type-Writers, of which the following is a specification, reference being had therein to the accompanying 10 drawing.

This invention relates to attachments for typewriters, and the invention has for its object to provide the paper support of a typewriter with a novel guide which can be easily 15 and quickly adjusted to engage the edge of the piece of paper being written upon, whereby if the paper is temporarily removed from the machine, it can be exactly replaced with the specified margin.

20 It is a well known fact that when a manuscript with carbons and carbon papers are removed from a typewriting machine, that it is rather difficult to properly replace the same, whereby the writing upon the carbon 25 copies will correspond with the writing upon the original copy. Providing the ends of the carbon copies and the original copy are evenly matched, my improved guide attachment will insure a correct position of the 30 manuscript papers in a typewriting machine, this being accomplished without interfering with the mechanism of a typewriter and without much labor.

The invention will be hereinafter described 35 in detail, and reference will now be had to the drawings wherein,

Figure 1 is a perspective view of a detachable paper support of a typewriting machine, equipped with the attachment, Fig. 2 is a 40 cross sectional view of the same, illustrating an end view of the attachment, and Fig. 3 is a front elevation of a paper support, illustrating the manner in which the attachment correctly positions papers.

45 In the accompanying drawings, 1 designates a portion of the carriage of a typewriter, having a detachable pivoted paper support 2 for supporting and guiding a piece of paper 3 beneath the platen-roll 4 of a type- 50 writer.

Upon the rear side of the support 2 at the right hand end thereof, I solder or otherwise secure a channel-shaped guide 5 to a slotted

plate 6, the end of said plate being contracted to provide an extension 7 having a 55 forwardly extending arm 8, the end 9 of which is bent upwardly. The slotted plate 6 is adjustably held in engagement with the guide 5 by a set screw 10 extending through the slot 11 of said plate, and engaging in the 60 guide 5.

The guide 5 and the plate 6 can be graduated as at 12, whereby the arm 8 can be set any desired distance from the end of the paper support 3. For instance, where a piece 65 of work is removed from the typewriting machine, and is not to be completed for some time, the distance of the arm 8 from the end of the support 3 can be marked upon the piece of work, whereby prior to placing the work in the machine, the arm 8 can be adjusted to properly position the piece of work. This is hardly necessary in the majority of instances, as the arm 8 simply serves as an object against which the edges 70 of original and carbon copies can be placed, when the copies are being positioned in a machine.

The attachment insures perfect and clean 75 work and saves considerable time when replacing an original and carbon papers and copies in a machine. The attachment is constructed of light and durable metal, and can be easily secured to the paper supports of various writing machines.

Having fully described my invention, what I claim and desire to secure by Letters Patent, is:—

An attachment for typewriters comprising the combination with a rearwardly-extending paper table, of a flanged graduated guide secured to one side thereof, a slotted plate mounted between the flanges of said guide and having one end provided with an extension, a forwardly projecting arm integral 90 with said extension and having the end thereof bent upwardly, and a set-screw extending through the plate and engaging the guide for securing the plate in various fixed positions.

In testimony whereof I affix my signature in the presence of two witnesses.

ALLEN W. CROUSHORE.
